[57] CLAIM

The ornamental design for a combined door and advertising display unit for a merchandising cooler, as shown and described.

DESCRIPTION

FIG. 1 is a perspective view of a combined door and advertising display unit for a merchandising cooler, showing our new design;

FIG. 2 is a top plan view thereof;

FIG. 3 is an end elevational view thereof;

FIG. 4 is a top perspective view thereof.

The broken line disclosure of a merchandising cooler and indicia in all views is for illustrative purposes only and forms no part of the claimed design.
